US00D913342S

(12) **United States Design Patent** (10) **Patent No.:** **US D913,342 S**
(45) **Date of Patent:** **** Mar. 16, 2021**

(54) **DIVIDER**

(71) Applicant: **Deere & Company**, Moline, IL (US)

CN 302092321 S 9/2012
CN 302220180 S 12/2012

(72) Inventors: **Steve A. Coon**, Long Grove, IA (US);
Troy M. Heims, Davenport, IA (US)

(73) Assignee: **DEERE & COMPANY**, Moline, IL
(US)

(**) Term: **15 Years**

(21) Appl. No.: **29/712,589**

(22) Filed: **Nov. 8, 2019**

(30) **Foreign Application Priority Data**

May 9, 2019 (EM) 006435152

(51) **LOC (13) Cl.** **15-03**

(52) **U.S. Cl.** **D15/28**
USPC .....

(57) **CLAIM**

The ornamental design for a divider, as shown and described.

DESCRIPTION

FIG. 1 is a perspective view of a divider according to our new design;

FIG. 2 is a first side elevational view thereof;

FIG. 3 is a second side elevational view thereof;

FIG. 4 is a first end elevational view thereof;

FIG. 5 is a second end elevational view thereof;

FIG. 6 is a first plan view thereof;

FIG. 7 is a second plan view thereof;

FIG. 8 is a perspective view of a divider according to another embodiment of our new design;

FIG. 9 is a first side elevational view thereof;

FIG. 10 is a second side elevational view thereof;

FIG. 11 is a first end elevational view thereof;

FIG. 12 is a second end elevational view thereof;

FIG. 13 is a first plan view thereof; and,

FIG. 14 is a second plan view thereof.

The dash lines depict environment subject matter that forms no part of the claimed design.

1 Claim, 10 Drawing Sheets
